THREAD-CONTROLLING DEVICE

Rudolph Becker, North Plainfield, N. J., assignor
to The Singer Manufacturing Company, Elizabeth, N. J., a corporation of New Jersey

Application February 28, 1942, Serial No. 432,735

7 Claims. (Cl. 112—201)

This invention relates to sewing machines and more particularly to the stitch-forming instrumentalities of the single-thread chain-stitch rotary looper type sewing machine.

In certain classes of work, such as necktie stitching, exceptionally loose stitches are required to give the resultant seam the proper amount of elasticity. In order to produce such loose stitches an exceptionally large loop of thread must be drawn out of the rising needle and as this loop, when shed by the looper, is not set tightly up to the work by the take-up mechanism, it frequently happens that this loosely drawn up needle-thread loop is reseized by the looper before the loose stitching is drawn up through the needle-aperture in the throat-plate by the action of the feeding mechanism. It is, therefore, an object of the present invention to overcome the above cited stitching difficulties by provision of a thread-guard or deflector for the loosely set up needle-thread loops, which will prevent reseizure of such loops by the looper before they are fed out of range of the looper.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front elevation of a sewing machine embodying the present invention.

Fig. 2 is a left end view of the machine shown in Fig. 1.

Fig. 3 is a bottom plan view of the elements upon the under side of the work-support adjacent the sewing point.

Fig. 4 is a sectional elevation, on an enlarged scale, of the work-support and the stitching instrumentalities shown in Fig. 2.

Fig. 5 is a bottom plan view of the throat-plate with the present invention applied thereto.

Fig. 6 is a side view of the thread-guard shown in Fig. 5.

Fig. 7 is a bottom plan view of a section of fabric containing a line of loosely set up single-thread chain-stitches.

Fig. 8 is a vertical section taken substantially along line 8—8 of Fig. 7.

Referring more specifically to the drawings, the invention is disclosed as embodied in a sewing machine having a frame comprising a base 10,

standard 11, and an overhanging arm 12 which terminates in a hollow head 13. A main, or needle-bar-actuating shaft 14 is journaled lengthwise of the arm 12 and mounted at its rear end is a combined belt- and hand-wheel 15. The forward end of the shaft 14 actuates, by means not herein shown, a reciprocatory needle-bar 16 which is suitably journaled in the head 13 and carries an eye-pointed needle 17 at its lower end. Also mounted in the head 13 is a spring-pressed presser-bar 18 to the lower end of which is secured, as by a clamp-screw 19, a presser-foot 20.

Cooperating with the presser-foot 20 to effect step-by-step movements of the work between successive reciprocations of the needle 17, is a feed-dog 21 which operates through slots 22 in the throat-plate 23. This feed-dog 21 is adapted to be given backward-and-forward and rising-and-falling movements such as are common in conventional four-motion feeding mechanisms. These movements are effected by suitable mechanism located within the base 10 of the machine. A more detailed disclosure of the present feeding mechanism may be had by reference to my U. S. Patent No. 2,222,017, dated Nov. 19, 1940.

Mounted in the base 10 of the machine is a rotary shaft 24 carrying upon its outer end a conventional rotary wing-type chain-stitch loop-taker 25 which cooperates with the needle 17 in the formation of single-thread chain-stitches. Suitable mechanism within the machine frame effects rotation of the loop-taker 25 in timed relation with the reciprocations of the needle 17. For a more complete disclosure of the present loop-taker and needle-actuating mechanisms reference may be had to my U. S. Patent No. 2,222,016, dated Nov. 19, 1940.

The machine is also fitted with the thread-controlling and take-up mechanisms of my patent application Serial No. 423,914, filed Dec. 22, 1941, and comprising essentially the needle-bar thread take-up element 26, the pull-off arm 27 cooperating with the thread-guard 31, the double disk tension 28, and the thread-nipper unit 29. The needle-thread 30 is delivered from a supply source, not herein shown, directly to the usual double disk tension unit 28 from which it is threaded through the eyelets of the thread-guide 31, and then it is led backwardly through a stationary eyelet 32 to the thread-nipper unit 29. From the nipper unit the thread is led forwardly through a pair of stationary eyelets 33 directly to a stationary thread-guide generally designated by the numeral 34. Finally the thread is led from the guide 34 to the eye of the take-up

element 26 and then downwardly between the guide disks 35 to the needle 17.

Supported upon the base 10 of the machine is the usual cloth-plate 36 in which is set and secured, as by screw 37, the throat-plate 23 provided with an elongated needle-aperture 38. It is to be understood that in most all single-thread chain-stitch sewing machines an elongated needle-aperture is required so that proper room will be provided for both the rising cast-off needle-loop and the descending thread-carrying needle.

Mounted upon the bottom surface of the throat-plate 23 by means of a fastening screw 39 is the shank 40 of the thread-guard having a reduced portion 41 and an active edge 42. The fastening screw 39 passes through an enlarged aperture 43 in the thread-guard thereby permitting the thread-guard to be adjusted lengthwise and sidewise of itself. As may be best seen in Figs. 4 and 5, the thread-guard is disposed in parallel relation with the throat-plate and the active edge 42 is spaced from the throat-plate and underlies and extends across the elongated needle-aperture 38, in a direction transverse to the direction of feed. Having the active portion 42 of the thread-guard spaced from the throat-plate 23 prevents the cast-off needle-loop 50 from being caught between the throat-plate and the thread-guard.

Figs. 7 and 8 illustrate a body material 44 having a line of loosely set-up single-thread chainstitches placed therein. It is to be noticed that in order to provide the proper amount of elasticity in the body material 44 the concatenated loops 45 are set within the body material in a very loose manner. To produce such loose stitches in a machine of the present type the take-up mechanism is adjusted so that it will pull only a small quantity of the cast-off needle loop back up into the body material, thus leaving an abnormally large portion of the loop depending from beneath the under surface of the material.

In Fig. 4 of the drawings, the needle 17 has just begun to rise and the beak 46 of the looper is about to enter the needle-thread loop 47 formed by the rising needle and it is also about to enter the loop 48 of thread previously expanded by the looper and detained at this time in the throat 49 thereof. Just prior to this time the loop 50 was cast off from the looper and it was drawn up through the needle-aperture by the combined actions of the take-up and feeding mechanisms. However, the loop 50 being abnormally large, is not drawn up sufficiently close to the work to eliminate danger that the loop 50 will be caught a second time by the looper beak. Therefore, the present thread-guard has been provided so that its active portion 42 will engage the loop 50 as the work is being fed prior to the descent of the needle and wipe such loop upwardly and in a direction opposite to the direction of feed, thus removing the loop from the path of the looper. As shown in Fig. 4, the active portion 42 of the thread-guard is sustaining the loop 50 in its upwardly deflected position and therefore the looper beak 46 cannot engage the same. When the needle 17 rises completely out of the fabric 44 the feeding mechanism will shift the work past the needle-aperture to thus completely draw the loop 50 up through the needle-aperture.

Having thus set forth the nature of the invention what I claim herein is:

1. In a sewing machine, in combination, a

thread-carrying needle, means for reciprocating said needle, a rotary chain-stitch looper cooperating with said needle in the formation of stitches, needle-thread take-up means, a throat-plate, means to feed the work over the throat-plate, and a thread-guard disposed below said throat-plate, said thread-guard being adapted to engage the cast-off needle-loop and to deflect said loop upwardly and in a direction opposite to the direction of feed.

2. In a sewing machine, in combination, work-feeding means, a thread-carrying needle, means for reciprocating said needle, a looper cooperating with said needle in the formation of stitches, said looper having its loop-seizing movement in the direction of the feed of the work, needle-thread take-up means, a throat-plate having a needle-aperture therein, and a thread-guard having its active portion underlying and extending across said needle-aperture at a point rearwardly of the needle-path, said thread-guard being adapted to engage the cast-off needle-loop and to deflect said loop upwardly and in a direction opposite to the direction of feed.

3. In a sewing machine, in combination, work-feeding means, a reciprocatory thread-carrying needle, a chain-stitch looper having its loop-seizing movement in the direction of the feed of the work, and needle-thread take-up means all cooperating in the formation of loosely set up stitches, a throat-plate provided with a needle-aperture therein, and a thread-guard having its active portion underlying and extending across said needle-aperture in the rear of the needle-path, said work-feeding means being adapted to draw each cast-off needle-loop over the active portion of said thread-guard so as to deflect each loop upwardly and in a direction opposite to the direction of feed.

4. In a sewing machine, in combination, a reciprocatory thread-carrying needle, a rotary chain-stitch looper and needle-thread take-up means, all cooperating in the formation of loosely set up stitches, a throat-plate having an elongated needle-aperture therein, work-feeding means, and a thread-guard having its active portion underlying and extending across said elongated needle-aperture in the rear of the needle-path, said work-feeding means being adapted to draw each cast-off needle-loop over the active portion of said thread-guard so as to deflect each loop upwardly and in a direction opposite to the direction of feed.

5. In a sewing machine, in combination, a thread-carrying needle, means for reciprocating said needle, a looper having a loop-seizing movement and cooperating with said needle in the formation of stitches, take-up means adjusted to set the stitches so that loosely set up needle-thread loops extend downwardly from the work, a throat-plate having an elongated needle-aperture therein, a thread-guard having its active portion underlying and extending across said needle-aperture at a point rearwardly of the needle-path, and feeding means adapted to impart to the work a component of movement in the direction of loop-seizing movement of the looper, said feeding means being also adapted to draw each of said loosely set up needle-thread loops over the active portion of said thread-guard so as to deflect each loop upwardly and in a direction opposite to the direction of feed.

6. In a sewing machine, the combination with a thread-carrying needle, means to actuate said needle, a rotary chain-stitch looper cooperating

with said needle in the formation of stitches, work-feeding means operative to feed the work in one direction, and a throat-plate having a needle-aperture therein, of a thread-guard secured to and in parallel relation with the bottom surface of said throat-plate, said thread-guard comprising a substantially flat metal strip having one edge thereof underlying and extending across said needle aperture at a point rearwardly of the needle-path and in a direction transverse to the direction of feed, said thread-guard cooperating with said work-feeding means so as to deflect each cast-off needle-loop upwardly and in a direction opposite to the direction of feed.

7. A sewing machine having, in combination, a reciprocatory thread-carrying needle, a plate-member provided with a needle-aperture through

5 which said needle reciprocates, a loop-taker positioned at one side of said plate-member and complementary to said needle in seizing a thread-loop presented by said needle and enchaining said thread-loop with a preceding thread-loop expanded by said loop-taker prior to casting off said expanded thread-loop, a feeding mechanism for advancing work past said needle, and a member extending across the line of feed rearwardly of the path of needle-reciprocation and providing an abutment against which the cast-off thread-loop is moved by the advance of the work to deflect said cast-off loop out of range of the loop-taker as the latter advances to seize a subsequent needle-thread-loop.

10 15 RUDOLPH BECKER.
